16 // Inventor:

Thomas H. Rideout.

⁸ Henry J. Miller, atty.

UNITED STATES PATENT OFFICE.

THOMAS H. RIDEOUT, OF CAMBRIDGE, MASSACHUSETTS, ASSIGNOR TO T. H. RIDEOUT MANUFACTURING COMPANY, A CORPORATION OF MASSACHUSETTS.

OVEN-SHELF.

1,206,730.

Specification of Letters Patent. Patented Nov. 28, 1916.

Application filed October 25, 1915. Serial No. 57,789.

To all whom it may concern:

Be it known that I, THOMAS H. RIDEOUT, a citizen of the United States, residing at Cambridge, in the county of Middlesex and 5 State of Massachusetts, have invented new and useful Improvements in Oven-Shelves, of which the following is a specification, reference being had to the accompanying drawings, forming part thereof.

10 This invention has reference to improvements in shelves and particularly to improvements in shelves adapted for use in ovens.

One object of this invention is to so construct a shelf that it may be readily adjusted relative to its width and that at any width, within its limits of adjustability, its load carrying member may easily be drawn out with its load whereby inspection of and access to said load are facilitated.

Another object of the invention is to provide a shelf having a novel slidable load carrier or member.

Other objects of the invention will appear 25 from the following description.

The invention consists in the novel construction of the adjustable load carrying member and its frame.

The invention also consists in such other 30 novel features of construction and combination of parts as shall hereinafter be more fully described and pointed out in the claims.

Figure 1, represents a front view of the 35 improved shelf in position in an oven, the latter being indicated. Fig. 2, represents a plan view of the shelf. Fig. 3, represents a sectional view taken on line 3—3 Fig. 2.

Similar characters of reference designate 40 corresponding parts throughout.

As shown in the drawings in its preferred form the improved shelf comprises a main frame having the ways or tracks 5, 5 bent at their rear ends to furnish the overlapping 45 arms 6, 6 which are slidably connected, for adjustment, by the guides 7, 7. Attached to the front ends of the ways or tracks 5, 5 are the members 8, 8 having the bent ends 9, 9 and the inwardly extending overlapping

50 arms 10, 10 which latter are slidably connected by the guides 11, 11. At the rear portions of the ways or tracks 5, 5 are secured the members 12, 12 which correspond in some degree to the members 8, 8 in that 55 these members 12, 12 have the outwardly

bent ends 13, 13 and the feet 14, 14. These feet 14, 14 and the guides 11, 11 support the main frame on the bottom of an oven O or on any plane surface as indicated at X in Fig. 3. The outwardly bent ends 9, 9 and 60 13, 13 respectively of the members 8, 8 and 12, 12 afford extensions to which are secured the strips or bars 15, 15 adapted to be received by brackets B, B at the sides of the oven O or by any other suitable sustaining devices. In order to prevent the tipping upward of the rear end of the main frame I prefer to provide one of the arms 6, 6 with the clip or clamp 16 to adjustably secure the rod 17 which latter may extend to the top of 65 the oven O as shown in Fig. 1.

The front members 8, 8 of the main frame are provided with the rotatable sheaves 18, 18 which sustain the riding side bars 19, 19 of the shelf which side bars have the 70 inwardly bent and overlapping arms 20, 20 slidably connected by the guides 21, 21, these rear portions of the side bars 19, 19 having the frames 22, 22 each furnished with a pair of rotatable sheaves 23, 24, between which 75 the ways or tracks 5, 5 of the main frame are engaged.

The front ends of the shelf side bars 19, 19 are connected by members 25, 25 depending from said side bars and having the overlapping arms 26, 26 slidably connected by the guides 27, 27. These arms 26, 26 with those marked 20, 20 are in pairs which are rigidly connected together by the members 28, 28 and the overlapping portions of said arms 26, 26 and 20, 20 are connected by the members 29, 29 without thereby restricting the adjustable slidability of said overlapping arms 26, 26 and 20, 20. Each pair of 80 said members 28, 29 is connected by cross 85 bars 30, 30 which clear the member 29 of the other of said pairs of members.

From the above description and by reference to the drawings it will be seen that the main frame is adjustable laterally to various 90 sizes, in view of the pairs of slidable arms 6, 6 and 10, 10 and that, in such adjustment, as the shelf is engaged with the ways or tracks 5, 5 of said main frame by its sheaves 18, 18, 23, 23, and 24, 24, such adjustment of 95 the main frame will effect the adjustment of the shelf; that is, the main frame and the shelf are both constituted by pairs of complementary members, the respective pairs being engaged. Thus the main frame and the 100 105 110

shelf are both constituted by pairs of complementary members connected for lateral adjustment while the individual members of the frame and shelf are so engaged by said 5 track and sheaves that the lateral adjustment of the main frame effects corresponding adjustment of the shelf and vice versa.

In use, the main frame sustains the shelf, in an oven, in such manner that drawing outward 10 of the shelf and its load, and the retractive movement of the same are facilitated; this feature is particularly desirable when the load on the shelf consists of a heavy roast which it is desirable to inspect from 15 time to time as the tipping of the shelf when drawn outward is prevented.

Having thus described my invention I claim as new and desire to secure by Letters Patent—

20 1. A shelf mechanism comprising a main frame and a shelf each constituted by pairs of slidably adjustable members, said shelf members having means engaged with the frame whereby said shelf follows all adjusting movements of the frame.

25 2. A shelf mechanism comprising a main frame having a pair of ways each having in-

wardly extending overlapping arms, guides for slidably connecting said arms, a shelf having rigid side members and pairs of inwardly extending overlapping arms, means for slidably connecting said latter arms, and means mounted on said rigid side members to slidably receive the ways of said main frame whereby the ways of said frame and 30 said shelf are positively connected and all lateral adjusting movements of either are transmitted to the other.

3. A shelf mechanism comprising a main frame, having pairs of ways, arms extending 40 inward from said ways and slidably connected, grooved sheaves rotatably mounted relative to said ways, and a shelf constituted by a pair of adjustably connected members each of which has a track received in the related grooved sheave of said main frame, and a pair of grooved sheaves mounted on members of said shelf to receive the respective ways of said main frame whereby said main frame members and shelf members are 45 positively engaged by said sheaves and each follows all adjusting movements of the other.

THOMAS H. RIDEOUT.
